UNITED STATES PATENT OFFICE.

MAX BAUM, OF NEW YORK, N. Y., ASSIGNOR TO RADICE ELECTRIC CO., INC., A CORPORATION OF NEW YORK.

DESIGN FOR A STRAP FOR LIGHTING FIXTURES.

Application filed September 6, 1927. Serial No. 23,304. Term of patent 3½ years.

To all whom it may concern:

Be it known that I, MAX BAUM, a citizen of Poland, residing in New York, county of Bronx, and State of New York, and doing business at 19 West Moshula Parkway, in said city, have invented a new, original, and ornamental design for a Strap for Lighting Fixtures, of which the following is a speci-

fication, reference being had to the accompanying drawing, forming part thereof.

Figure 1 is a front view, and

Figure 2 is a side view.

I claim:

The ornamental design for a strap for lighting fixtures, substantially as shown.

MAX BAUM. [L.S.]
